ELECTRIC RAZOR SUPPORT

Arthur R. Wahl, Crestview, Md.

Application September 9, 1938, Serial No. 229,155

4 Claims. (Cl. 248—314)

This invention relates to a device for supporting an electric razor when the same is not in use, and the primary object of the present invention is to provide a device of this kind which is simple, inexpensive in construction, and efficient in use.

A more specific object of the present invention is to provide a support of the above kind including a socket-like receptacle into which the electric razor may be readily inserted and from which the razor may be conveniently withdrawn.

Still another object of the present invention is to provide a support of the above kind having means to facilitate mounting thereof in connection with an electrical wall socket, whereby the support is efficiently mounted to derive current from the wall socket for the operation of the razor.

A still further object is to provide a support of the above kind having a plug receptacle into which the attachment cord of the razor may be readily plugged, and provided with a switch for controlling the flow of current from the wall socket to said plug receptacle so that the current may be turned off when the razor is placed in the supporting receptacle and not required for use, and whereby the current may be turned on for operation of the razor when the latter is withdrawn from the support for use.

Other objects and features of the present invention will become apparent from the following description when considered in connection with the accompanying drawing, and the invention consists in the novel form, combination and arrangement of parts hereinafter more fully described, shown in said drawing and claimed.

In the drawing:

Figure 1 is a front elevational view of an electric razor support constructed in accordance with the present invention and operatively mounted in association with an electrical wall socket.

Figure 2 is a view thereof in side elevation and in vertical section.

Figure 3 is a rear elevational view of the support per se.

Figure 4 is a horizontal section on line 4—4 of Figure 1; and

Figure 5 is a vertical section of a modified form of the holder employing a switch for automatically cutting off the flow of current to the razor when the latter is placed in the holder or support.

Referring in detail to the drawing, the present holder or support is in the nature of a socket-like receptacle whose socket decreases in width near the bottom, so that the conventional electric

razor R will fit and be sustained therein. The receptacle includes a rear wall 5, side walls 6 and front walls 7 which may increase in thickness at the bottom so that the socket afforded by the receptacle is contracted at the bottom to have the razor R rest thereon at its lower end for being sustained within the receptacle as shown clearly in Figure 1. The side walls 6 are provided with slots 8 that extend downwardly from the top of such walls so that the user may grasp the sides of the razor to facilitate withdrawal of the latter from the support or holder. The receptacle is open at the bottom to provide for passage of the attachment cord 9 of the razor as well as the connector 10 by means of which said attachment cord is connected with the razor R at the bottom of the latter. The lower portion of the receptacle is provided at the front with a slot 11 of sufficient width to permit passage of the attachment cord 9 therethrough, said slot being extended to the top of the receptacle and increased in width at the top so that the razor may be placed in the holder without being elevated entirely above the latter. This construction also avoids the necessity of threading the attachment cord into the holder through the bottom of the latter when the razor is placed in the holder. The rear wall 5 may have openings 12 for reception of screws or the like whereby the device may be attached to a wall or other vertical support.

I prefer to provide the holder with means for mounting the same in connection with an ordinary electrical wall socket so that current may be derived from the latter for operation of the razor. The ordinary wall socket 13 having the usual slots with contacts therein is suitably mounted in a recess of the wall 14 and this recess is usually covered by a face plate 15 attached by screws 16 and provided with a central opening through which the socket 13 is exposed. I propose to use the screws 16 for attaching the holder, the latter being passed through the openings 12 in the rear wall 5 of the holder so that the latter is flatly and rigidly secured against the face plate 15 as shown clearly in Figures 2 and 4. In the back of the rear wall 5 I provide a recess 17, and attached to this rear wall within the recess 17 are rearwardly projecting contact pins 18 adapted to enter the slots of the wall receptacle 13 and engage the contacts therein to derive current therefrom when the holder is mounted in connection with the wall socket as described. Arranged within the recess 17 are conductors 19 extending to contacts 20 of a plug receptacle 35

formed in the lower portion of the holder at one side of the latter and adapted for reception of the contact pins of the attachment plug 21 usually provided on the other end of the attachment cord 9. By plugging the plug 21 into the receptacle including contacts 20, current may be derived for operation of the razor, as will be apparent. The recess 17 may be closed by a cover plate 22 suitably secured in place and having slots through which the contact pins 18 project. Also mounted within a side of the holder near the bottom of the latter is a suitable switch 23 interposed in one of the conductors 19 for controlling the flow of current from the pins 18 to the contacts 20. In the embodiment of Figures 1 to 4 inclusive, a manually operable switch is provided having a projecting handle 24 for manual actuation thereof. In the embodiment of Figure 5, the switch 23 has an inwardly projecting plunger or operating member 24a which may be moved by the weight of the razor when placed in the holder for breaking the circuit or cutting off the supply of current to the razor. This switch may be of a generally well known normally closed type which will automatically close the circuit when the razor is removed from the holder. As switches of this type are well known in the art and as the same forms no specific part of the present invention, detailed illustration and description thereof is believed unnecessary. Otherwise, the form of Figure 5 is identically the same as the form of Figures 1 to 4 inclusive, and like parts are indicated by similar reference characters in all of the views. While one end of the attachment cord 9 could be permanently connected with the holder with its wires attached to the conductors 19, it is preferred to provide the receptacle including contacts 20 so that the attachment cord may be removed or renewed whenever found desirable. Of course, if the usual screws at 16 which fasten the face plate 15 in place, are not long enough, longer screws may be supplied with the holder so that they may pass through the rear wall 5 and enter the part 25 into which they are threaded for securing both the face plate 15 and the holder in position. In practice, the holder is simply placed against the face plate 15 so that the contact pins 18 enter the contact containing slots of the receptacle 13, whereupon the screws 16 are inserted and threaded into the part 25 so as to rigidly secure the face plate and the holder in place. When this is done, current is derived from the receptacle 13 and the flow of the current to the razor may be readily controlled by the switch 23. By mounting the holder near a mirror in a bathroom or other suitable place, the razor is supported in a position for convenient use. The holder may be conveniently and efficiently mounted, and the razor will be effectively supported out of the way when not required for use.

While I have shown and described in considerable detail preferred embodiments of the invention, it is to be understood that the invention is capable of further modification and changes in details of construction without departing from the spirit and scope of the invention as claimed.

What I claim as new is:

70 1. A holder or support for an electric razor comprising a receptacle providing a socket open at the top and tapering smaller at the bottom

to snugly receive and retain the razor therein, said receptacle being provided with a restricted opening at the bottom for downward passage of the attachment cord of the razor therethrough and formed of a rear wall, two side walls, and front walls spaced apart to permit forward and rearward passage of the attachment cord therebetween, said side walls having slots therein extending downwardly from the top thereof to permit grasping of the sides of the razor to facilitate removal of the latter from the holder. 10

2. A holder or support for an electric razor comprising a receptacle providing a socket open at the top and tapering smaller at the bottom to snugly receive and retain the razor therein, said receptacle being provided with a restricted opening at the bottom for downward passage of the attachment cord of the razor therethrough and formed of a rear wall, two side walls, and front walls spaced apart to permit forward and rearward passage of the attachment cord therebetween, said side walls having slots therein extending downwardly from the top thereof to permit grasping of the sides of the razor to facilitate removal of the latter from the holder, the major upper portions of the front walls being cut away at their adjacent edges to permit removal of the instrument from the receptacle upon slight elevation of the razor relative to the bottom of said receptacle. 30

3. A holder or support for an electric razor comprising a receptacle providing a socket open at the top and tapering smaller at the bottom to snugly receive and retain the razor therein, said receptacle being provided with a restricted opening at the bottom for downward passage of the attachment cord of the razor therethrough and formed of a rear wall, two side walls, and front walls spaced apart to permit forward and rearward passage of the attachment cord therebetween, contact pins carried by and projecting rearwardly from said rear wall for engagement in a wall socket, means for connecting the attachment cord of the razor to said receptacle and in electrical connection with said contact pins, a switch carried by said receptacle for controlling the flow of current to said attachment cord, and means for securing the holder in connection with the wall socket. 35

4. A holder or support for electric razors comprising a receptacle open at the top and provided with a bottom opening for passage of the attachment cord of the razor therethrough, said receptacle tapering smaller at the bottom for supporting engagement with the razor and formed of a rear wall, side walls and front walls spaced apart to permit passage of the attachment cord therebetween, said side walls having slots therein extending downwardly from the top thereof to permit grasping of the razor for facilitating removal of the latter from the holder, means to mount said holder upon a wall or other vertical support, contact pins carried by and projecting rearwardly from said rear wall for engagement in a wall socket, a plug socket 65 formed in said holder, conductors in said rear wall connecting the contact pins with the contacts of said socket, and a switch carried by the holder and interposed in one of said conductors for controlling the flow of current to the razor. 70
